MOP

Frederick A. Speik and Gertrude K. Forbes,
South Pasadena, Calif.

Application November 9, 1933, Serial No. 697,234

2 Claims. (Cl. 15—120)

Our invention relates to a mop and, in particular, to the conventional house mop in which a swab, consisting of a plurality of strings or cords which are fastened together at their lower ends, is detachably secured by means of a clamping head to the end of a handle.

It is an object of this invention to provide a wringer permanently attached to the mop whereby the swab may be quickly and efficiently wrung whenever that operation becomes necessary or desirable and the wringer may be moved instantly out of interference with the swab.

With the above and other objects in view, which will appear as the description proceeds, our invention consists of the construction and arrangement of parts hereinafter described and claimed.

In the accompanying drawings we have illustrated a preferred embodiment of our invention, and in which:

20 Fig. 1 is a side elevation of a mop provided with our wringer, parts being in section and parts being broken away, and showing the wringer in inoperative position.

Fig. 2 is a similar view to Fig. 1 showing the 25 wringer removed from its position alongside the handle and in operative position wringing the swab.

Fig. 3 is a section on the line 3—3 of Fig. 1.

Fig. 4 is a view similar to Fig. 1 showing a 30 slightly modified form.

Fig. 5 is a front elevation showing the jaws of the clamping head of the mop and the lower part of the wringer, the swab being shown in section.

Fig. 6 is a front elevation of the wringer removed from the mop.

Fig. 7 shows a vertical section of another modification of our mop wringer with the wringer attachment in inoperative position.

Fig. 8 shows a similar view to Fig. 7 with the 40 wringer attachment in operation.

Figs. 9 and 10 are sections on the line 9—9 and 10—10, respectively, of Fig. 7.

Figs. 11 and 12 are sections taken on the line 11—11 and 12—12, respectively, of Fig. 8.

45 Referring to the drawings, 10 indicates a mop handle provided at its lower end with a clamping head shown as a unity by the numeral 11. This clamping head consists of an upper stationary jaw member 12 provided with a ferrule 13 which is secured to the handle 10 and a lower movable jaw member 14 co-acting with the stationary jaw 12, the lower jaw 14 being provided with a pair of oppositely disposed arms 15 which are secured to a toggle lever 16, the lower end of which is 50 secured to a compression spring 17 encircling the

handle 10 whose lower end abuts against the ferrule 13. By throwing the lever 16 in a clockwise direction the lower jaw 14 will be moved downwardly away from stationary jaw 12, as will be understood, while in the position shown in Figs. 1, 2, and 4 the tension of the spring 17 will move the lower jaw 14 into clamping position to securely hold the swab 18.

The swab 18 consists of an elongated, flexible mass of strings or fabric cords having the ends of the cords secured together, as by sewing through tapes 19. The ends of the swab are folded over each other, in the position shown in Fig. 1, through the open jaws 12 and 14, then clamped together to form a loop with one of the ends of 15 the swab within the loop as shown at 20 and the other outside the loop as shown at 21.

The mop thus far described is the subject matter of a copending application of one of the joint inventors, Gertrude K. Forbes, for Mop, filed June 15, 1933, Serial No. 675,913, and while we prefer to use this type of mop any other suitable type of mop may be used in which the swab is in the form of a loop or where the outer end of the swab has the ends of the strings or cords fastened together.

The wringer for wringing the swab is shown as a unity in Fig. 6 removed from the mop and indicated by the numeral 22. It consists of a corrugated heavy wire or bar 23 having leg portions 24 extending at its outer ends at right angles thereto, leg portions 24 being bent again inwardly at 25 and then upwardly to form a loop 26 which is disposed within a handle grip 27 and securely fastened thereto by any suitable means, such as a ferrule 28 surrounding the lower part of the grip 27 and provided with a triangular head 29 enclosing the lower portion of the loop 26. The wringer 22 is associated with the mop by passing the ends of the swab 19 and 20 through the loop formed by the bar 23, legs 24, and members 25 so that the corrugated bar 23 lies adjacent the movable jaw member 14, as shown in Figs. 1 and 4. The handle grip 27 is held adjacent and parallel to handle 10 by means of a spring clip 30 secured to handle 10 by a screw 31. The lower portion carrying the corrugated bar 23 is offset at an angle at 32 so that the bar 23 lies adjacent and parallel to the movable jaw 14.

In Figs. 4 and 5 a modified form is shown in which movable jaw 14 is provided with a downwardly extending channel or groove which is formed by a strip of metal 32 bent about the movable jaw 14 for the reception of the upper ends of the corrugated parts of the bar 23, the 55

object being to hold the corrugated bar 23 stationary in addition to the clamp so as not to interfere with the mopping operation of the swab.

In the modification illustrated in Figs. 7 to 12, 5 inclusive, the mop handle 40 is made hollow, consisting of an upper section 41 and a lower section 42 made of sheet metal. The clamping head 43 consists of an upper, stationary, transverse member 44 provided with a collar 45 fitting within 10 the lower end of the handle section 42 and to which it is secured by welding or any other suitable manner. The movable jaw member 46 co-acting with the stationary jaw member 44 is operated by means of a toggle lever 47 pivoted to the 15 upper end of a helical compression spring 48 encircling the lower end of the handle section 42.

The mop wringer comprises a gear housing 49 connecting the adjacent ends of handle sections 41 and 42 in which a beveled gear 49 is driven by 20 a gear 50 in mesh therewith. A handle 51 fast to shaft 52 and secured to gear 50 imparts rotary motion to the driven bevel gear 49 through which a wringer rod 53 is slidably mounted. The rod 53 is provided at its upper end with a bearing 54 25 slidably engaging the inner wall of the handle section 41. A handle grip 55 projects from the bearing 54 through a longitudinal slot 56 made in the face of the handle section 41. A key slot 57 is provided in the rod 53 in sliding engagement 30 with a key 58 in the gear 49. The lower end of the rod 53 passes through a perforation 44' in the stationary jaw 44 and is provided at its extreme lower end with a head 59 on which a mop gripper 60 is mounted. The mop gripper 60 consists of 35 a rectangular frame made of a metal bar comprising a member 61 mounted in head 59 for pivotal movement on a horizontal plane. From the ends of the member 61 short lateral members 62 connect the same to a member 63 parallel to the 40 member 61.

The swab 64 consists, preferably, of two units instead of one, described in connection with the mop wringer shown in Figs. 1 to 6, inclusive. The same are assembled one on each side of the rod 45 53 and passing between the stationary and movable jaws 44 and 46, respectively, and also through the gripper frame 60, as clearly shown in Figs. 7, 11, and 12.

Operation

50

The mop is used in the ordinary manner in mopping up a floor. Referring to the modification shown in Figs. 1, 4, and 5, when it is desired to wring the swab the handle grip 27 is removed 55 from the clip 30 and swung downwardly and into the position shown in Fig. 2. The lower end of handle 10 or the inner end of the swab is now grasped with one hand and the handle grip 27 is now turned with the other hand so as to wring 60 the water from the swab 18, as illustrated in Fig. 2. The rotation of the handle grip 27 is now reversed to straighten out the loop in the swab 18 and the handle again moved into inoperative position on clip 30.

65 In the modification shown in Figs. 7 to 12, inclusive, the mop is used in the position shown in Fig. 7 when mopping the floor. It should be

noted that in this position the rod 53 is moved to its extreme upper position by moving the handle 55 upwardly along the slot 56 in the handle section 41. The gripper frame 60 is swung on its pivot with the mop end passing therethrough until it rests on the stationary jaw 44, the rear side of which is slightly curved to provide a seat 44² on which the member 63 of the gripper 60 rests. It may be necessary to compress the swab slightly between the movable and stationary 10 jaws so as to enable the member 63 to slip over the extreme outer end of the seat 44². When it is desired to wring the mop the gripper 60 is removed from its seat 44² and the rod 53 is now slid downwardly until the member 61 of the gripper 15 60 engages the inside end of the swab 64. When in this position the handle 51 is manually rotated thereby through the gears 50 and 49 imparting rotary motion to the rod 53 and also to the gripper 60 whereby the swab 64 is twisted, as 20 shown in Fig. 8, thereby compressing the strands of the swab 64 and wringing out the water. The rotation of the handle 51 is now reversed until the swab 64 hangs smooth. The rod 53 is now moved upwardly into the position shown in Fig. 7 25 and the gripper is again slipped on to its seat 44².

Various changes may be made in the construction and arrangement of parts by those skilled in the art without departing from the spirit of our invention as claimed.

We claim:

1. A wringing mop comprising an elongated hollow handle, a wringer rod slidably and rotatably mounted in said handle and in retracted inoperative position projecting a short distance 35 through the lower end thereof, means to rotate said rod and means to slidably extend it a greater distance through said lower end of the handle to wringing position, a looped mop swab, means for securing said looped mop swab to the lower 40 end of said handle, a laterally extending projection on the lower end of said handle, and a closed-loop frame swingably mounted on a transverse axis on the lower end of said rod to embrace and secure the looped swab and to swing over said 45 projection to hold the rod in retracted inoperative position.

2. A wringing mop comprising an elongated hollow handle, a wringer rod slidably and rotatably mounted in said handle and in retracted inoperative position projecting a short distance 50 through the lower end thereof, means to rotate said rod and means to slidably extend it a greater distance through said lower end of the handle to wringing position, a looped mop swab, means for 55 securing said looped mop swab to the lower end of said handle, a closed loop frame swingably mounted on a transverse axis on the lower end of said rod to embrace and to secure the looped swab and means on said handle positioned to engage said closed loop frame when the latter is 60 swung back into contact with said last named means to hold said rod in retracted inoperative position.
